(57) **CLAIM**

The ornamental design for a fecal occult blood analyzer, as shown and described.

DESCRIPTION

FIG. 1 is a front view of a fecal occult blood analyzer, of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top plan and left side perspective view thereof;

FIG. 8 is a rear, bottom plan and right side perspective view thereof;

FIG. 9 is an enlarged cross-sectional view with the inner mechanism omitted along the line 9-9 in FIG. 3;

FIG. 10 is an enlarged cross-sectional view with the inner mechanism omitted along the line 10-10 in FIG. 3; and, FIG. 11 is an enlarged cross-sectional view with the inner mechanism omitted along the line 11-11 in FIG. 3.

The broken lines showing portions of the fecal occult blood analyzer form no part of the claimed design. The dot-dash broken lines in the drawings represent the bounds of the claimed subject matter, the dot-dash lines, themselves forming no part thereof.

1 Claim, 11 Drawing Sheets
